Albert W. Gray. • Middleton, Comt.

Letter 3 Patent

The Schedule referred to in this Letter Patent and making part of the same containing a description of the merits of the invention. Albert W. Gray himself of his improvement in the corn sheller.

To all whom these presents shall come: I do, et. known thys, Albert W. Gray of Middleton in the County of Rutland and State of Vermont have invented a new and useful improvement in the corn sheller, as in the machine used for shelling corn, and that the following is a full and exact description thereof. The machine invented by me the said Albert may be made either of wood or metal, and consist of a rotary circular plate or wheel about fourteen inches in diameter, standing perpendicular, one or both surfaces of this plate (as shall best suit the writer) is thickly studed with points made of iron projecting from one surface to three eighths of an inch. These points are placed either in rows converging towards the centre, (see Plate annexed Fig. 1. A) or promiscuously, (B) and are generally about one half inch apart. Through the centre of this plate is placed a horizontal shaft (T.) from one to eleven inches long, resting upon two bearings, on one end of this shaft is a pinion two and one half, or three inches diameter. This pinion (Fig. 2. B. & C.) is moved by a perpendicular cog wheel, four inches in diameter (Fig. 2. M. & N.) which is the beater to which the power is applied (Fig. 2. O.) giving motion to the rotary plate which is principally intended in the operation of shelling, as the power may be applied immediately to the end of the shaft (Fig. 1. T.) giving less motion to the plate and of course shelling the corn more slowly. It consists also of a conductor or square tube having a cavity for inclosing long round stones, and a pair of iron rods. The upper and lower pieces are fast parallel and far enough apart to admit rods of iron. The side is fastened at one end with a hinge, so as to give the other play or backward and forward motion. This conductor is placed over the rotary plate (Fig. 1. C. D.) with the open side up-

Mar 31, 1836

The coils on the surface are inclined and in such a position that when placed in the elevated end of the conductor in their passage through it may strike the surface of the rotary plate just above or just below a live stream through the center. The coils of wire thus placed are drawn through the conductor by a draft made by the points upon the rotary plate when in motion during the process of shelling and the coil passes off at the depressed end of the conductor a spring is placed back of the movable side of the conductor (Fig. 1. G. & D.) which serves to press the coil of wire upon the surface of the rotary plate and by contracting and enlarging the passage as it is to adjust itself to the different sizes of different coils of wire, so to shell both large and small coils entirely clean the conductor must be placed as far from the rotary plate that the coils of wire may completely separate, or down wards, during the process of shelling. The lower part of the conductor (Fig. 3. E. & F.) is perforated and the lower end cut short so as to allow the coils when shelled to fall through but the passage is continued to the place where the coil is discharged by means of wire placed parallel to a wire web. A wire is placed so as to operate upon the spring which passes upon the movable side of the conductor giving a greater or less pressure as may be required. When the rotary plate lies flat upon both sides a double conductor is placed in similar manner to the foregoing, thereby enabling a double machine to be used by the same power. The rotary plate, conductor and spring are made generally with a base 6 by 18 inches square and 14 inches deep with a small opening at the bottom to allow the coils to escape. There is also a recess at each end of the conductor to receive through the base at the elevated end is a hopper and at the lower end the base is discharged. This may be fastened permanently or may be portable placed upon standards. It is usually put in motion by manual power, but may be moved by the application of other power. The foregoing are sufficient to be the most convenient proportions to be used in the construction of the aforesaid live shell but may be varied without impairing the ^{many} advantages, or to suit the wishes of purchasers. The machine may also be made to shell faster by doubling the number of rotary plates or double rotary plates upon the same shaft and have one conductor to each plate or two conductors to each double plate. The double rotary plates should be arranged upon the wire commonly or have left

Mar. 31, 1836

having two points on both sides of the plate instant, one side or surface.
 I do not claim as my own invention any part of said machine separately
 from except the ^{inner} conductor, and the said improvement of said rotary plate or
 solid wheel. But what I do claim as my own invention and for which I
 ask Letters Patent of the United States on the above described machine
 is not being before known or used are, First, the said conductor. Second
 by the said improvement of said rotary plate. and Thirdly, the following
 combination of parts - viz. such a rotary plate or wheel as the one
 described in my invention which said plate is moved and applied
 to effect the object of shelling corn and combined with the conductor spring
 hinge and screw as before described so constructed as to adjust itself to the top
 front edge of the different ears of corn, and also to keep the ears of corn on
 their proper place while passing across the plate, giving them a proper slope
 and separating the cobs from the corn combined also with the hinge as before de-
 scribed as placed as to cause the ears of corn to be raised and strike the outer
 rotary plate at the proper place.
